JOHN J. DUFFIE, OF BERKELEY, CALIFORNIA, ASSIGNOR TO VACUUM SPECIALTY MANUFACTURING CO., OF SAN FRANCISCO, CALIFORNIA, A CORPORATION OF ARIZONA.

VACUUM-CLEANER.

1,133,543.

Specification of Letters Patent. Patented Mar. 30, 1915.

Application filed August 20, 1913, Serial No. 785,701. Renewed February 25, 1915. Serial No. 10,614.

To all whom it may concern:

Be it known that I, JOHN J. DUFFIE, a citizen of the United States, residing at Berkeley, in the county of Alameda and State of California, have invented new and useful Improvements in Vacuum-Cleaners, of which the following is a specification.

This invention relates to vacuum cleaners of the volume type, or those in which the suction is induced by a centrifugal fan; the cleaning being done by the indraft of a relatively large volume of air at high velocity.

The object of the present invention is to provide a simple, practical machine, either for stationary or portable use, but particularly designed as a portable cleaner for use in homes and in which machine the usual settling bag is done away with and in place thereof there is an especially designed metal removable dust-collection chamber.

One of the chief objections to vacuum cleaners using a dust-collection bag is the disagreeable feature of emptying the bag and cleaning it. In my construction an easily removable receptacle is employed which can be very conveniently emptied.

Other objects will appear hereinafter.

The invention consists of the parts and the combination and construction of parts as hereinafter more fully described and claimed, having reference to the accompanying drawings, in which—

Figure 1 is a longitudinal vertical section illustrating the invention. Fig. 2 is a horizontal section on line X—X Fig. 1, with a portion of the upper fan case partially broken away. Fig. 3 is a section on line W—W Fig. 1, showing the stationary inwardly deflecting vanes between the fan.

A represents a case of suitable size and shape, the lower portion of which forms a housing for the motor 2 and the fans 3—4, while the upper part of the case above the fans is adapted to receive a removable dust receptacle 5. This removable dust receptacle telescopes and fits inside of the top of the case A and has its bottom contiguous to a partition plate 6 in case A. Plate 6 has a central hole 7 registering with the eye 8 of the upper fan and with the tube or air column 9 which is carried by and projects upwardly within the receptacle 5. The weight of the receptacle 5 is supported on the top rim of case A by means of the out-

side peripheral flange 10 formed on the telescoping receptacle 5.

11 is a strainer of suitable filtering material which rests on top of receptacle 5 and has a central hollow sleeve 12 fitting snug over the upper slightly tapered mouth of the tube or conduit 9.

13 is a cover fitting the top of the filter 11 and inclosing with the filter the upper air passage-way or chamber 14.

Suitable packing, not here shown, may be interposed between the contiguous edges of the cover 13, the filter 11, the receptacle 5 and the casing A; the parts when so assembled being suitably clamped to form air-tight joints by appropriate means, as the clamping bolts 15; the construction and mode of operation of which are well known.

In operation the air from the suction tool, or any number of tools, according to the capacity of the machine, is admitted into the chamber 16 in the receptacle through the pipe 17; the latter being preferably curved and arranged so as to discharge the air circumferentially against the curved wall of chamber 16 whereby the air will swirl around the chamber and allow the heavier solid particles and refuse to settle in receptacle 5. Under the action of the fans the air is then drawn up through the filter 11 into chamber 14 and thence down the conduit 9 through the eye 8 of fan 3; being discharged at the peripheral outlet 18. Between the fans 3 and 4 is a partition 20 on the upper side of which are the stationary vanes 21 by which the air discharged at high velocity through the outlet 18 is directed back to the central opening 22 in plate 20 where it is picked up by the second fan 4 and finally discharged at accelerated velocity at 23, into the motor chamber 24 whence it is allowed to escape freely to the outer atmosphere; the draft of air through chamber 24 serving to keep the motor 2 cool.

The construction of the filter 11 while of any suitable form preferably embodies an annular rim 25 having a downwardly projecting annular flange 26 to telescope over the outside edge of the receptacle 5; the fabric of the filter being clamped between the ring rim 25 and an underneath ring plate, which may be of light sheet metal; suitable adhesive being employed to keep the parts together. The flange sleeve 12 is

passed through a central hole in the filtering fabric and is glued or otherwise suitably secured thereto.

The motor is preferably directly connected 5 to the fans so as to run them at maximum velocity and I prefer a multi-stage fan or turbine construction for obvious practical reasons. The method of directing the air from the first fan to the second by means of 10 the partition 20 and deflectors 21 is a very practical and simple expedient. The orifice 7 in plate 6 which constitutes the inlet to the fan chambers has a cross area of such size that it will not allow more air to go through 15 than the fans can handle without over-taxing the motor. In other words, in order to economize power a small motor is used to drive a fan or fans which latter could if their air inlet was uncontrolled, be so operated 20 as to over-load the motor and burn it out. The size of this orifice is determined by experiment and is a mere matter of engineering skill.

The chief feature of the present invention 25 is the removable receptacle 5 and filter 11 whereby all the disadvantages of the settling bag are done away with.

The device as now constructed is very 30 compact, of few parts and readily accessible. Manifestly various changes may be made 35 in the details of construction herein shown and described without departing from the invention. It is also manifest that any suitable type of suction inducing means may be 40 employed.

I claim:

1. In a vacuum cleaner, the combination 45 of a casing inclosing a motor and suction apparatus, and a removable receptacle fitting in the top of the casing and over the

suction apparatus, said receptacle having a central upwardly extending air column opening through the bottom of the receptacle into the suction apparatus, a cover, a removable filter medium between said cover 45 and said receptacle encircling the column and inclosing with the receptacle an air inlet chamber, and a single means for locking the cover, receptacle and casing together, and thereby clamp the filter medium in 50 place, said chamber in the receptacle having an air inlet, said parts so constructed and arranged that on the operation of the motor air is drawn into the receptacle thence through the filtering medium and thence 55 outwardly through the column into and through the suction apparatus.

2. In a vacuum cleaner, the combination 60 of a casing inclosing a motor and suction apparatus, a removable receptacle fitting in the top of the casing over the suction apparatus, said receptacle having a central upwardly 65 extending tube opening through the bottom of the receptacle into the suction apparatus, the upper portion of said tube being tapered to form a seat, a cover, a removable filter medium resting on the top of said receptacle beneath the cover, a tapered collar centrally located in said filter and adapted to engage the upper tapered portion of the tube, and a common means for locking the cover, receptacle and casing together to securely 70 clamp the parts in position.

In testimony whereof I have hereunto set 75 my hand in the presence of two subscribing witnesses.

JOHN J. DUFFIE.
